G. O. SQUIER

AERIAL ATTACHMENT DEVICE FOR RADIOFREQUENCY SIGNAL SYSTEMS

Filed June 24, 1922

INVENTOR
George Owen Squier
BY his ATTORNEY'S
Dwight & Dwight

UNITED STATES PATENT OFFICE.

GEORGE OWEN SQUIER, OF DRYDEN, MICHIGAN.

AERIAL ATTACHMENT DEVICE FOR RADIOFREQUENCY SIGNAL SYSTEMS.

Application filed June 24, 1922. Serial No. 570,701.

This invention relates to a device for use in connection with standard telephone equipment to permit the reception or transmission of radio frequency signals without the use of other aerial or guide for the radio frequency signals.

The object of the invention is to provide a device of this character which is simple in construction, efficient in operation and economical of manufacture.

A further object of the invention is to provide a device which will enable the utilization of telephone wires as either an aerial or as a guide in carrier current telephony or telegraphy in connection with a radio frequency receiving or transmitting apparatus wherein no permanent attachment is effected between the radio frequency signaling apparatus and the telephone system.

A further object of the invention is to provide a device of this character wherein the normal operation of the telephone is not interfered with by the receipt of radio frequency signals.

A further object of the invention is to provide a device of this character which is controlled by the relative position between the device and a standard transmitter and receiver unit.

Further objects of the invention will appear more fully hereinafter.

The invention consists substantially in the construction, combination, location and relative arrangement of parts, all as will be more fully hereinafter set forth, as shown in the accompanying drawing and finally pointed out in the appended claims.

Referring to the drawings:

40 Figure 1 is a view in perspective illustrating the attachment of my invention with the telephone receiver and transmitter assembly positioned at right angles relative thereto (at an abnormal position).

45 Fig. 2 is a view in side elevation of the telephone and device of my invention positioned for the reception or transmission of radio frequency.

50 Fig. 3 is a diagrammatic view partially in section of the base of the telephone unit and the device of my invention.

Fig. 4 is a fragmentary sectional view of a slightly modified arrangement embodying my invention.

55 Fig. 5 is a plan view of the same. The same part is designated by the same

reference character wherever it occurs throughout the several views.

It is among the special purposes of my present invention to provide a device of exceedingly simple construction which may be employed to permit the utilization of ordinary telephone wires as an antenna for the receipt or transmission of radio frequency signals, or as the guide wire for wired wireless, or, as it is sometimes called, carrier current telephony or telegraphy, in the manner as set forth generically in my patents issued to me as follows: No. 980,356, granted Jan. 3, 1911, No. 980,357, granted Jan. 3, 1911, No. 980,358, granted Jan. 3, 1911, No. 980,359, granted Jan. 3, 1911.

I accomplish this in accordance with my invention without interference in any way with the telephone system or with the radio frequency signaling system, that is, neither system interferes with the normal operation of the other, and further, no permanent connection is made between the two systems.

My invention may be applied in many forms and, therefore, I do not desire to be limited or restricted to any particular form or arrangement, but I have found a most artistic arrangement to be that shown in the drawing and which is selected for the purpose of illustrating the invention herein involved.

In the drawing, reference numeral 1 designates the usual telephone standard provided with a base 2 at one end and the receiver or transmitter at the other end. The usual telephone hook 4 supports the usual telephone receiver 5 which receiver is connected to the base 2 by the wire cord 6. The usual wire cord (not shown) extends from the base to the usual telephone box containing the call bell etc. (not shown). In the standard telephone equipment thus described, it is customary to cover the bottom of the base 2 with felt 7 or other material. And the telephone is assembled and held in assembled position by means of three screws 8. To permit access to the screws and thus permit repairmen to disassemble the telephone, holes are provided in the felt or other covering 7 for the base 2 where the said screws 8 are located.

The device of my invention consists of a standard 9 made of any suitable material, preferably non-conducting material, such as

wood, which may be finished in any desired color. The base 9 is formed with a circular cup recess 10 in the top thereof of substantially the same diameter as the 5 largest diameter of the base 2 so that the base 2 of the telephone standard 1 may set snugly in the cup recess 10. A wire connector enters the base 9 and is electrically connected through a suitable condenser 10^a 10 preferably one having a capacity value less than .01, to a pin 12 positioned at the approximate center of the base 9 and it is normally and yieldingly projected upwardly by means of a spring 13 which bears against 15 a collar 14 secured to the pin 12. The spring also is seated against the bottom 15 of the base 9. When it is desired to utilize the device in connection with a telephone system whereby the telephone wires are available as 20 a radio antenna or as a guide for carrier current or wired wireless signals, the telephone stand is merely placed on the base 9. The pin 12 of the device of my invention comes in contact with the center screw 8 in 25 the bottom of the base 2 of the telephone standard 1 and is held in electrical contact therewith by means of the spring 13. All the electrical connection necessary for the efficient operation of the radio signaling apparatus employed in connection with the 30 system is thus effected and obviously there is no permanent or semi-permanent connection between two systems by reason of the employment of the device of my invention, 35 and furthermore, there is no interaction of interference between the two systems, either of which being operably independent of the other, or both of them being operable simultaneously.

40 The end of the wire cord 11 is provided with some form of attachment, for example, a tip 20 to facilitate attachment of the device to the radio frequency signaling apparatus. For the reception of signals it is 45 attached to the usual terminal employed for connection with the antenna in a radio receiving set, the rest of the equipment being that commonly employed in radio frequency signaling. Obviously the device may be employed for transmission of radio frequency 50 signals as well as reception. Also, I have found that the length of the cord 11 may be varied within wide limits without affecting the efficient operation of the apparatus 55 employed.

It may sometimes be desirable to vary the capacity of condenser 10^a, and consequently in Figs. 4 and 5, I show a variable condenser of standard structure in place of the fixed condenser 10^a. Variation of the capacity of the condenser is effected through a handle which extends through the side or peripheral wall of the body 9 through a slot provided for that purpose. Of course it is obvious 65 that any other type of variable condenser

may be employed, the one shown and just described being selected merely for the purpose of illustration.

Many further modifications and changes in detail will readily occur to those skilled in the art without departing from the spirit and scope of my invention as defined in the claims. But having now set forth the objects and nature of my invention and having shown and described a construction embodying the principles thereof, what I claim as new and useful and of my own invention and desire to secure by Letters Patent, is:

1. In a device of the character described, a body adapted to form a receptacle for the base of a telephone instrument, means carried by said body for effecting an electrical contact with a metallic portion of the base of said instrument, a wire connected with said means and extending from said body, and means included in said body for preventing low frequency telephone currents from flowing through said wire connection. 89

2. In a device of the character described, a body adapted to form a receptacle for the base of a telephone instrument, means carried by said body for effecting an electrical contact with a metallic portion of the base of said instrument, a wire connected with said means and extending from said body, 95 and a condenser carried in said base and included in said wire connection.

3. In a device of the character described, a body adapted to form a receptacle for the base of a telephone instrument, means carried by said body for effecting an electrical contact with a base screw of said telephone instrument, a wire connection with said means and extending from said body, and means included in said body for preventing low frequency telephone currents from flowing through said wire connection. 100

4. In a device of the character described, a body adapted to form a receptacle for the base of a telephone instrument, means carried by said body for effecting an electrical contact with a base screw of said telephone instrument, a wire connection with said means and extending from said body, and a condenser carried in said base and included in said wire connection. 110

5. In a device of the character described, a body adapted to form a receptacle for the base of a telephone instrument, a centrally disposed yieldable metallic pin carried by said body for effecting an electrical contact with a metallic portion of the base of said instrument, a wire connection with said means and extending from said body, and means included in said body for preventing low frequency telephone currents from flowing through said wire connection. 115

6. In a device of the character described, a body adapted to form a receptacle for the base of a telephone instrument, a centrally 120

- disposed yieldable metallic pin carried by said body for effecting an electrical contact with a metallic portion of the base of said instrument, a wire connection with said means and extending from said body, and a condenser carried in said base and included in said wire connection. 5
7. In a device of the character described, a body adapted to form a receptacle for the base of a telephone instrument, a centrally disposed yieldable metallic pin carried by said body for effecting an electrical contact with the centrally positioned base screw of said instrument, a wire connection with said pin extending from said body, and means included in said body for preventing low frequency telephone currents from flowing through said wire connection. 10
8. In a device of the character described, a body adapted to form a receptacle for the base of a telephone instrument, a centrally disposed yieldable metallic pin carried by said body for effecting an electrical contact with the centrally positioned base screw of said instrument, a wire connection with said pin extending from said body, and a condenser carried in said base and included in said wire connection. 15
9. In a device of the character described, a body adapted to be associated with a telephone instrument without interference with the normal operation thereof, means carried by said body for effecting an electrical contact with a metallic portion of said instrument, a wire connection with said means and extending from said body, a condenser included in said wire connection, and means for varying the capacity of said condenser. 20
10. In a device of the character described, a body adapted to form a receptacle for the base of a telephone instrument, means carried by said body for effecting an electrical contact with a metallic portion of the base of said instrument, a wire connected with said means and extending from said body, a condenser carried in said base and included in said wire connection, and means for varying the capacity of said condenser. 25
11. In a device of the character described, a body adapted to form a receptacle for the base of a telephone instrument, means carried by said body for effecting an electrical contact with a base screw of said telephone instrument, a wire connection with said means and extending from said body, a condenser carried in said base and included in said wire connection, and means for varying the capacity of said condenser. 30
12. In a device of the character described, a body adapted to form a receptacle for the base of a telephone instrument, a centrally disposed yieldable metallic pin carried by said body for effecting an electrical contact with a metallic portion of the base of said instrument, a wire connection with said pin 35 and extending from said body, a condenser carried in said base and included in said wire connection, and means for varying the capacity of said condenser. 40
13. In a device of the character described, a body adapted to form a receptacle for the base of a telephone instrument, a centrally disposed yieldable metallic pin carried by said body for effecting an electrical contact with the centrally positioned base screw of said instrument, a wire connection with said pin extending from said body, and means included in said body for preventing low frequency telephone currents from flowing through said wire connection. 45
14. In a device of the character described, a body adapted to form a receptacle for the base of a telephone instrument, a centrally disposed yieldable metallic pin carried by said body for effecting an electrical contact with the centrally positioned base screw of said instrument, a wire connection with said pin extending from said body, a condenser carried in said base and included in said wire connection, and means for varying the capacity of said condenser. 50

In testimony whereof I have hereunto set my hand on this 21st day of June A. D., 1922.

GEORGE OWEN SQUIER.
